CHASSIS LUBRICATION

Joseph Bijur, New York, N. Y., assignor to Auto Research Corporation, a corporation of Delaware

Application September 20, 1930, Serial No. 483,165

32 Claims. (Cl. 184—7)

The present invention, considered in its broader aspects, is concerned with the automatic lubrication of machinery from a central source of lubricant, but finds its preferred embodiment in the field of chassis lubrication. The following specification, therefore, while recognizing the broader utility of the invention, will concern itself specifically with the problem of chassis lubrication and the manner in which the present apparatus satisfies the requirements of this type of machine. The more or less universal adaptability of the system to other machines, or groups of machines, will become apparent as the description proceeds.

An object of the invention is to provide a system of this character in which the feed of oil to the system is wholly automatic occurring periodically at cyclically intermittent intervals during normal running of the vehicle without the exercise of care or attention on the part of the operator, and so designed that emission of oil is prevented while the vehicle is standing still.

Another object is to provide for the immediate application of the fresh lubricant to the bearings whenever a car that has been long idle is set in motion, this auxiliary or emergency lubricant feed occurring independently of the regular lubricant feed cycles.

Another object is to provide an efficient and automatic mechanism for controlling the periods of pump effectiveness.

Other objects will be in part obvious during the course of the following specification and will be in part pointed out therein.

In a preferred embodiment of the invention, the supply device embodies a force pump by which successive small charges of lubricant from a central reservoir are forced into the distributing conduit system, thus subjecting the distributing system to a rapidly succeeding series of pressure impulses by which the lubricant is forced through the restricted outlets in proportions predetermined by proper calibration of such outlets.

During normal operation of the vehicle, timing mechanism renders the pump at cyclically succeeding intervals alternately effective and ineffective to deliver lubricant to the system.

The pump, preferably of the plunger type, may be conveniently embodied in a unitary structure at the bottom of the lubricant reservoir, and the timing mechanism may also be conveniently housed in or intimately associated with the reservoir.

Preferably, the pump plunger is of relatively small diameter and a relatively small operating impetus applied thereto is operative to cause a material rise in pressure in the conduit system, which is at all times filled with substantially incompressible lubricant. Thus, regardless of lubricant viscosity, a more or less uniform volume of

oil will enter the system at each effective reciprocation of the pump.

Among various sources of power for pump actuation, I have shown a plurality of modes of utilizing vibratory energy developed in vehicle travel. The vibratory impulses may be applied to the pump from an associated oscillating or swinging inertia member.

When the vehicle is running at a constant speed, the vibration-sensitive inertia actuated member will tend to vibrate rapidly so that either the capacity of the pump should be exceedingly minute, or the periods of effective pump operation short and infrequent.

There are many ways in which the pump might be rendered ineffective at the desired intervals, such, for instance, as the automatic mechanical disconnection of the pump from its power source, the automatic closing of the inlet or outlet valves of the pump, the by-passing of the pump discharge back to the reservoir, or the cutting off of the supply of lubricant at some point in the pump intake line. In the present case, the latter mode of procedure is preferred, especially in view of the fact that a gravity oil feed to the pump is used. Gravity flow is up through a freely vented filter chamber located below the pump level, and by overflow from this chamber to the pump. By cutting off the flow from the reservoir to the filter chamber, the pump, after using up the small quantity of oil which has overflowed from the chamber, simply runs idly until communication between reservoir and filter chamber is restored.

The timing mechanism may be actuated by various means to periodically open and close a flow valve between reservoir and filter chamber. One effective form of control is directly from the pump actuating means so that the pump will be rendered inoperative after the plunger has been reciprocated a predetermined number of times. The timing means may conveniently include a valve operating reduction gear train operated from the pump actuating mechanism by a step by step arrangement such as a ratchet and pawl.

The auxiliary or emergency priming means which assures immediate supply of lubricant to the bearings of a car after it has long stood idle preferably includes a priming chamber having an outlet into the pump intake line, between the main supply valve and suction line, and arranged to accumulate oil by slow seepage from the reservoir. Thus, even though the main control valve be closed, the pump will have an auxiliary supply of lubricant available to meet the special requirements of such emergency starting conditions.

The invention may be more fully understood

from the following description in connection with the accompanying drawings, wherein:

Fig. 1 is a perspective fragmentary view of an automobile, the chassis of which is lubricated in accordance with the invention.

Fig. 2 is a detail of one of the drip plugs of the system.

Fig. 3 is a vertical sectional view through an automatic liquid supply and feed apparatus constructed in accordance with the invention.

Fig. 4 is another vertical sectional view therethrough taken approximately on the line 4-4 of Fig. 3.

Fig. 5 is a sectional plan view taken on the staggered line of 5-5 of Fig. 3.

Fig. 6 is a view similar to Fig. 3 but illustrating a modification and taken on line 6-6 of Fig. 7.

Fig. 7 is a sectional plan view on the line 7-7 of Fig. 6.

Fig. 8 is an enlarged vertical sectional detail taken approximately on line 8-8 of Fig. 7.

Fig. 9 is an elevational detail of the mechanism for controlling the operative and inoperative periods of the pump.

Fig. 10 is an enlarged detail view of the force pump shown in Fig. 3.

Fig. 11 is a top plan view of the jiggle weight, and

Fig. 12 is a top plan view of vibration transmitting mechanism of Fig. 6.

In Fig. 1 there is diagrammatically shown mounted on the dashboard of a vehicle 10, a lubricant reservoir and pump unit 11. The pump at intermittent intervals discharges through the fitting 12 to the distributing system consisting of conduits 13, preferably liquid filled and non-dilatable, which extend along various structural parts of the vehicle and deliver through drip plugs 14 to the various bearings.

The supply unit of the present invention may be embodied in a wide variety of lubricant systems, one form of which is shown in my prior patents, No. 1,632,771, 1,732,212 and 1,746,139 which systems include a plurality of freely inter-communicating liquid filled distributing conduits, the outlets of which may be supplied with suitable metering devices. By way of example one of these metering devices, is illustratively shown upon Fig. 2. This device comprises a fitting 15 having a valve 16 with a seating facing 17 of varnished silk urged against and adapted to take the imprint of the sharp seat 18. Coiled compression spring 19 reacting against a retaining cup 20 presses the valve against its seat. A strainer 22 of wool-felt, backed with wire mesh 23 is plugged into the socket 21 at the opposite end of the fitting. Between the valve and the strainer is the restriction pin 24, fitting in a corresponding longitudinal bore. The flow resistance of the drip plug depends upon the precise diameter of the pin or wire 24, the bore of all drip plugs being of the same diameter, the rating of a plug being determined by selection of a pin of the proper diameter. In practice, each drip plug has a marking (not shown) which indicates its rating.

At the inlet of each drip plug fitting is a steel bushing 25, preferably press-fitted and retaining the strainer 22 in place. A threaded nut 26 reacts at its inner end against a compression coupling sleeve 28. The sleeve is wedged inwardly by the bushing 25 against the feed pipe 21 (a branch or end of one of the conduits 13) which at its outlet end abuts the shoulder 25' in the bushing 25.

Referring first with particularity to Figs. 3 to

5 inclusive, and 10 and 11, there is illustrated a unitary assemblage consisting of the reservoir R, the pump P arranged in a base casting of the reservoir, and a motor, such for instance as the jiggle weight W, the latter with its associated mechanism being preferably accommodated in a separate housing 93 on top of the reservoir. Lubricant from the reservoir flows gravitationally into a filter chamber C formed in the base casting at a lower level than the pump and upwardly through the filter F to the pump. The timing mechanism which periodically cuts off the flow of lubricant to the filter chamber and thereby causes the pump to run idly is preferably mounted within the reservoir and indicated generally at T.

More specifically, the reservoir itself consists of a pair of generally cup-shaped members, the upper inverted member 30 having a flanged mouth 31 receiving the mouth of the lower cup 32 and providing an overlap which may be welded. Member 30 is preferably provided with an integral upstanding filling neck 33 receiving a suitable vented closure cap 34.

The base casting, which in the present instance is disposed substantially below the bottom of the reservoir R, is reduced at its upper end as at 35 to receive a downwardly turned flange 36 of the lower cup 32. This flange defines an opening in the cup bottom which is shaped in accordance with the shape of the casting and the casting and flange may be conveniently welded or otherwise secured together in lubricant-tight relationship.

The casting may assume many forms. In the present instance as best seen in Fig. 5, it is of general pear-shape in horizontal cross section, the larger casting section 37 accommodating the filter chamber C and the smaller casting section 38 accommodating the pump P.

The filter chamber is formed by a downwardly facing socket 39 in the base casting into which is screwed a cup-like plug 40, seating against a packing ring 41 to prevent leakage of lubricant therearound and having a well or sediment trap 42 in its bottom. Filter F preferably comprises a pad or mat of wool-felt, the edges of which are clamped against a downwardly facing shoulder 43 in socket 39 by a cylindrical clamping member 44 resting on the bottom of the cup 40 and urged into mat clamping position as the cup is screwed home. The felt pad may be conveniently backed by a wire cloth screen 45, the edges of which are pressed by the mat against a second and higher downwardly facing shoulder 46 in the socket 39. Member 44 is of less diameter than the socket and defines with the socket wall an annular oil inlet space 44a from which the oil flows to the filter chamber proper through openings 53 in the member 44.

The means for controlling the gravitational flow of oil from the reservoir to the filter chamber includes a ball check valve 47 normally urged upwardly by coiled expansion spring 48 against a downwardly facing seat 49. The spring is backed against an upwardly facing shoulder 50 in a vertical bore 51 of the casting, this bore communicating with the filter chamber through an inclined passageway 52, which empties into the annular space 44a.

The enlarged upper end 54 of the vertical passageway 51 receives the pendant apron portion 55 of a valve casing 56, which provides the aforementioned valve seat 49. Oil from the reservoir passes to the valve through ports 57 in the cas-

ing 56. A pin 58 sliding in the casing acts when depressed to unseat the ball check 47. The high side of a cam 59 rotated by the timing mechanism, to be later described, is operative to periodically depress the pin 58 and unseat the valve 47.

The force pump P (Fig. 10) which receives oil from the filter chamber and delivers it to the conduit system 13 is of high power but of minute capacity. An upstanding post 60 integral with the base casting may be vertically bored to form the pump cylinder in which works the long metal pump 61 of a diameter which is approximately equal to or smaller than the diameter of the conduits 13 of the distributing system. The pump chamber is cooperatively formed by the inner upper end of a downwardly facing socket 62 in the casting and the top of a plug member 63 screwed into the socket. Preferably the flanged upper end 64 of the plug presses a packing ring 65 against the inner end of the socket and a flange 66 at the outer end of the plug presses a second packing ring 67 against the lower face of the casting. Block 63 is provided with a central vertical bore, the lower end 67' of which is enlarged and threaded to receive the nipple 68 on the fitting member 12. The upper end of this bore is reduced at 70 and its upper extremity is further reduced at 71. To the end of the plunger is attached a stem 73 which is adapted to crack open the valve 72 when the piston is in its lowermost position. The valve itself is normally spring-seated against a downwardly facing seat 74 in the bore 70 by the coil spring 75 backed against a cup member 76 press-fitted into the bore. The cracking open of the valve at the bottom of the plunger stroke permits the air compressed on the downward stroke of the plunger to escape from the pump cylinder and lessen the period of priming.

The inlet valve of the pump preferably comprises an annulus 77 resting on an upwardly facing seat 78 and communicating through a plurality of L-shaped passageways 79 with an annular groove 80 in the plug 63. Groove 80 receives oil from the top of the filter chamber through an inclined passageway 81. The annular inlet valve lifts automatically on the up-stroke of the pump plunger to an extent limited by stop pins 77a and is seated by the pressure of the entrapped lubricant as the plunger starts to descend.

It may be noted at this juncture that the use of such apparently delicate valving in connection with a high power, although small capacity pump, is rendered possible by the very effective filtering means which insures the passage of absolutely clean oil to the pump and prevents any minute foreign particles from reaching and lodging under the valves. The passageway 81 from the filter chamber to the pump is freely vented by a pipe 90 carried by a hollow plug 91 fitted into a vertical passageway 92 at the top of the base casting and intersecting the oil passage 81. The open top of the pipe 90 is preferably disposed above the top of the reservoir and desirably located within the housing 93 for the operating weight W. This housing is formed with a vent opening 94 and preferably comprises an inverted cup-shaped member welded, press-fitted or otherwise secured in telescoped relationship with a collar 95 on top of the reservoir.

In order to guide the vertical reciprocating movement of the weight actuated plunger operating rod 96, a bearing bushing 97 is secured in a suitable opening in the top of the reservoir. This bushing is of general cup-shape with its bot-

tom of substantial thickness to provide an adequate guide for the enlarged portion 98 of the rod. A collar 99 screwed into the upper threaded end of the bushing end 97 is centrally apertured at 100 for free passage to the pump rod and cooperates with the bottom of the bushing 97 to limit the range of vertical reciprocatory movement of the rod. This limiting action is attained by pinning a collar 101 to the rod between the telescoped members 97 and 99 so that they serve as stops for the collar and limit the upward and downward movement of the rod. The range of rod movement is readily adjustable by screwing the member 99 further into or out of its associated bushing. At its lower end, rod 96 is suitably connected to the axially aligned plunger of the pump, as by ball and socket joint 102.

At its upper end, within the housing 93, the rod carries a fixed disk 103, grooved at 104 near its outer edge to provide a seat for a coiled expansion spring 105, upon the upper end of which rests an outwardly extending flange 106 of the inertia weight W, whereby the weight is carried by the cushioning spring 105 and its load transmitted through the disk 103 to the rod 96 and the pump plunger 61. The weight is preferably mounted for vertical sliding movement on a sleeve 107 encircling the rod 96 above the enlargement 98. This sleeve at its lower end abuts a shoulder 98a defined by said enlargement. Hardened steel bushings 109 arranged within enlargements of the central bore 110 of the weight insure free sliding movement thereof on the sleeve 107. The sleeve 107 is held in position by a nut 111 screwed on to the top of the rod 96 and the movement of the weight in both directions is impositively limited by flat springs 112 and 113 arranged respectively at the top and bottom of the sleeve. In order to insure the desired cushioned impact against the flat stop springs, the upper and lower faces of the generally cylindrical weight are provided with circular recesses 114 so that the weight will strike only the ends of the springs.

On the upward movement of the weight, it will strike spring 112 and act through the nut 111 to lift the rod 96 and elevate the pump plunger 61 to an extent limited by the collar 99. As the weight gravitationally falls back, the load thereof is transmitted through the coil spring 105 to the pump rod so that the pump has a sharp, quick intake or suction stroke and a relatively slow but positive expelling stroke.

In normal operation of the vehicle the spring cushioned weight W may gradually develop a more or less periodic vertical sway or vibration, the amplitude of which will be considerably in excess of the range of the movement of the pump rod and the pump will be actuated in a substantially uniform manner by the jiggle weight. Violent vibrations, while productive of a wider range of movement of the weight, are inoperative to vary the effective stroke of the plunger.

Similarly the violence of such vibrations is inoperative to vary substantially the uniform speed of the reduction gear which acts to rotate the cam step by step and thereby intermittently unseat the valve 47. This reduction gear mechanism preferably includes a ratchet wheel 120 fixed on a horizontal shaft 121 mounted in journal bearings 122. These bearings may be formed by the circularly bent upper ends of vertical brackets or straps 123, welded, screwed or otherwise secured at 124 to the base frame. The ratchet wheel acts through a suitable intermedia-

ate gearing to rotate the cam 59 or rather the counter shaft 125 which carries the cam. This gearing, in the present instance, is illustratively shown as comprising a worm 126 on the shaft 5 meshing with a wheel 127 on the counter shaft 125.

The mechanism for imparting a step by step rotation to the ratchet wheel 120 includes a pawl 128 fixed upon one end of a horizontal lever 129, 10 the opposite end of which is pivoted at 130 to a bracket 131 secured to the inner face of the reservoir wall. Preferably, the lever consists of a pair of metal straps secured in side by side relationship and intermediate their ends flared outward- 15 ly in opposite directions to cooperatively define a sleeve 132 through which the pump rod 96 works.

To impart motion to the lever 129 from the reciprocating pump rod, a socket member 133 is preferably inserted in the upper end of the sleeve 20 132. A reactance collar 134 resting against a pin 135 in the pump rod backs a coiled expansion spring 136 encircling the pump rod and acting on the socket 133 to urge it against pin 137 on the pump rod. As the pump rod lifts on the impact stroke of the weight, it acts through the coil 25 spring 136 to elevate the lever 129 and move the pawl 128 back one step on the ratchet wheel. On the down stroke of the rod 96, pin 137 acts through the collar 133 to depress the lever 129 30 and causes the pawl 128 to feed the ratchet wheel 120 forwardly one step. Inasmuch as the pawl 128 is of the spring type and inasmuch as there is a certain amount of flexibility in the operating connections between the lever 129 and the pump rod, I may find it desirable to use an independent stop for limiting the retraction or 35 idle stroke of the pawl 128 and preventing any possibility of over-retraction. This stop, for the purposes of illustration, has been shown as a screw 138 adjustably mounted and backed in the 40 top of the reservoir R by nuts 139 engaging the inner and outer faces respectively of the reservoir top.

Preferably a conventional detent pawl 140 is 45 associated with the ratchet wheel to hold the latter against retrograde movement. This detent may be carried on an L shaped bracket 141 held in place by the screws 124. The pawl is urged into detaining position against the ratchet 50 wheel by a torsional spring 142.

The operation of the self-timing supply and feed unit, described above, is substantially as follows:

Assume that the cam 59 is in the position of Fig. 4 so that the ball check 47 is shut. Assume 55 also that the car is not in motion and that the filter chamber is substantially full of oil. When the car is started and operated in the usual manner, the jiggle weight W will immediately become active in the manner described above to 60 reciprocate the pump plunger and to impart a step by step feed movement to the ratchet wheel 120 of the reduction gear train. Inasmuch as the pump is free to suck air through the pipe 90, its reciprocation will be entirely idle and it 65 will simply compress and then relieve pressure on the air entrapped in the pump chamber. Since the piston 61 is unpacked, the air, when compressed, may leak with substantial freedom therearound. Some of the air sucked in through 70 the pipe 90 will thus find its way into the reservoir and bubbling up through the oil will escape through the usual vent opening in the closure cap 34.

75 The continued step by step rotation of the

ratchet wheel will gradually shift the position of the cam 59 until the cam depresses the pin 58 and opens the valve 47. When this occurs, the gradual seepage of oil through the filter disk F will fill the passageway 81 with oil and the filter disk F will fill the passage 81 with oil and the oil will rise in the pipe 90 seeking its own level. As soon as the pump begins to receive oil, it will become active to force a charge of oil into the piping system on each expelling stroke. The pressure exerted against the incompressible body of oil in the system by the small but powerful pump piston will be sufficient to force through the restricted outlets of such system a total quantity of oil equal to the increment which is supplied by the pump. In practice the periodicity of the weight vibrations and the correspondingly rapid action of the pump will result in application of a rapidly succeeding series of pressure impulses on the liquid which is confined in the system, these impulses following each other in such rapid succession and with such uniformity that the flow from the restricted outlets of the system is substantially equivalent to a continuous and uniform flow while the pump is pumping oil.

By the time the high side of the cam 59 has moved off pin 58 and the ball check 47 snaps to closed position, there may be a standing column of oil in the pipe 90. Whether or not such a column is present will be determined by the relative rates of oil seepage through the filter and the rapidity and capacity of the pump. Assuming such a column to be present, it will be used up by the pump even with the check 47 shut, after which the pump will again run idly until the cam goes around and again depresses the check valve 47. It will be noted that the system is one which prevents gravitational drainage of lubricant through the restricted outlets or drip plugs at times when the pump is operating idly. This is due to the fact that the pump outlet valve is never unseated except when increments of oil are being forced into the system by the pump, and since the drip plug valves are normally seated there will be no vent for the distributing system and no open outlet through which a drip could occur even though one of the drip plug valves were not fully closed.

In Figs. 6 to 9 inclusive, and Fig. 12, I have illustrated a modified form of construction which, while embodying certain of the principles shown in Figs. 3 to 5 has certain inherent advantages over the construction just described.

One essential difference is the fact that I use a pump of larger capacity and run it at much 130 more infrequent intervals. I provide an initial priming charge of oil so that oil will be supplied to the bearings whenever a car which has been standing idle for some time is set in motion. This arrangement precludes the possibility of 135 starting a car and running for some distance before oiling the bearings, even though the car has been stopped or stored during a normally idle period of the automatic feed pump. This form of invention is also suggestive of another manner in which vibratory energy may be successfully utilized for pump operation, the operating means in this instance comprising one of the spring shackles of the car, directly connected to the pump.

Here the reservoir R and its filling cap 34 are retained, but the base casting 150 is generally circular in formation and instead of being disposed without the tank and below it, is arranged for the most part within the tank proper and 150

- above the level of the tank bottom. Only the sediment trapping well 151 of the filter chamber 152 is disposed below the bottom of the reservoir. The filter chamber is substantially similar to that described above with one or two minor exceptions. The wire screen 153, which backs the filter pad F, instead of being pressed against a shoulder is provided with corrugations 154 and is pressed against the top wall of the chamber. Also the filter clamping collar 155 is in this case a part of the plug which forms the bottom of the chamber and the main inlet port 156 from the reservoir which communicates with the annular space 157 around the collar is a horizontal port controlled by a rotary disk valve 158. The filter chamber instead of venting through the passage which leads to the pump communicates by a transverse passageway 159 with a priming chamber 160, the latter having a vent pipe 161 at its top, terminating above the liquid level of the reservoir and supported at its upper end by a separate plate or bracket 162 projecting into the neck of the filling opening. The priming chamber 160 is formed by a downwardly facing socket in the base casting closed at its bottom by a block 163. Very slow seepage of oil into the priming chamber from the reservoir may occur through the highly restricted passageway 164 in the chamber wall. Due to the fact that the vent pipe 161 is disposed directly under the filling opening of the reservoir, this pipe and the priming chamber will, under ordinary conditions, become partially filled with oil through the top of the pipe whenever the reservoir chamber is recharged. The importance of this is that recharging may often occur only after the oil supply has been completely exhausted and during a period when the disk valve 158 is closed. In such a contingency, the oil will flow into the priming chamber through the passageway 157 and will immediately supply the pump with much needed lubricant for the distributing system, regardless of the position of the valve 158. As suggested above, the pump, in this case, is of larger capacity, the unpacked plunger 165 working freely in a cylindrical bore 166 in an upstanding projection of the casting. The diameter of the plunger and bore, may, if desired, be somewhat larger than the diameter of the lubricant filled conduits of the system which is to be supplied, so that larger increments of oil will be forced into the system at each expelling stroke of the pump. The fitting 167 through which oil flows to the various branches of the distributing system is screwed into the threaded bottom of a vertical bore 168 axially aligned with the pump plunger. A sleeve 169 screwed into this bore in advance of the fitting 167 provides a downwardly facing seat 170 for the pump outlet valve 171, the latter being normally held seated by coiled expansion spring 172. The pump inlet valve may be conveniently mounted in the short vertical passageway 173 which connects the filter chamber with the horizontal inlet passage 174 of the pump. In assembling the inlet valve, a collar 175 is forced upwardly against a downwardly facing shoulder 176 of the passageway 173 by a hollow plug 177 screwed into the passageway from the bottom. This plug is recessed to accommodate and provide a seat for the inlet valve 178 which is thus free to float between this seat and the collar 175. The inlet valve is lifted on the up-stroke of the plunger 165 and pressure seated on the expelling stroke thereof. The reduction gear train and the mechanism for operating it are quite similar to those described in connection with Fig. 3. A lever 180 has one end pivoted as at 181 on a bracket 182 fixed within the reservoir. The free end of the lever carries a driving pawl 183 co-acting with a ratchet wheel 184 carried by shaft 185 journalled in the upper ends of brackets 186 fixed to the base casting. The detent pawl 187 for the ratchet is pivotally mounted at 188 between ears 189 projecting from the post or cylinder 166' and the spring for urging this detent against the ratchet is shown at 190. The worm 191 on shaft 185 drives a gear which in the present instance serves as the rotary disk valve 158. This gear turns on the stub shaft 192 fixed to one of the brackets 186 and is spring pressed against the machined outer face 193 of the port 156 by a spring 194. The plunger operating rod 195 is journalled in a suitable bearing sleeve 196 pressed out of a plate 197 secured over an opening 198 in the reservoir top, and a petticoat 199 on the rod 195 protects the bearing opening for the rod 195 from rain and dust. The operative connections between the lever 180 and the pump rod are identical with those shown in Fig. 3 including the reactance disc 200 backing the spring 201 which acts through the collar 202 to lift the lever as the pump rod rises. As the pump rod falls, the pin 203 working against the collar 202 moves the lever downwardly. The means for translating vibratory energy into reciprocation of the pump rod is substantially identical with one of the means disclosed in my co-pending application Serial No. 296,975, filed August 2, 1928. The rod has a collar 204 pinned thereto at 205 and a coiled expansion spring 206 encircling the rod and backed against the plate 197 acts through the collar to urge the rod downwardly and the pump piston to discharged position. A coiled contractile spring 207 anchored to one of the usual spring shackles 208 of the vehicle serves to transmit through suitable mechanism the vibration of the vehicle spring. The intermediate mechanism includes a lever 209, one end of which is anchored through a suitable stud screw 210 and lock nuts 211 to the spring 207. This lever at its other end is bifurcated to straddle a rocking transmission plate 212, and the bifurcated extremity of the lever fulcrums on cross-pin 213 mounted in ears 214 rising from the plate 197. A torsional spring 215 encircling the pin 213 is engaged with lever 209 and tends to hold the free end thereof in lifted position. One end of the rocking transmission plate 212 is located under the intermediate portion of the lever 209 for depression by a contact boss 230 thereon. The other end of the transmission plate is apertured at 216 for the reception of the upper end of the pump rod, and nuts 217 screwed on to the rod above the plate cause the plate to lift the rod against the action of spring 206 when the transmission plate is rocked in a clock-wise direction. The plate 212 also rocks about the pin 213 to an extent limited by nuts 218 and 219 on a screw 220 secured in the reservoir top as by a nut 221. Plate 212 has an opening 221^a therein to receive the screw 220. The operation of the pump in this case is as follows: The continual oscillation of the vehicle spring 150

while the car is in motion will periodically draw down the lever 209 which by its pivotal engagement can slide freely with respect to its transmission plate at the contact boss 230. As the lever is depressed the transmission plate rocks about the pin 213 until it is arrested by the nut 219, this rocking movement of the plate serving to elevate the plunger rod 195 and thereby to complete the suction stroke of the pump plunger. 5 During the flexing return of the vehicle spring, torsional spring 215 restores the lever 209 to its illustrated position and the spring 206 is released to discharge the force-pump, and as an incident of such discharge swing the transmission plate back to position of Fig. 6. With this form of the invention the stop which limits the retraction of pawl 183 may conveniently comprise an extension 240 of the screw 220.

10 The operation of this form of self-timing intermittent feeding device is substantially as follows:

15 With the reservoir full of oil and with the disc valve 158 open, oil will flow gravitationally into the filter chamber 152 and up through the filter pad to the pump inlet valve 178. The charging or intake stroke of the pump exerts a substantial suction in the filter chamber sufficient to assist materially in drawing oil through the filter pad and not relying on seepage or gravity flow for charging purposes. On the discharge stroke, oil is forced past the outlet valve 171 and into the system. Periodically, and in fact during a large part of the time, the disc valve 158 will be closed and the pump will be operating 30 idly since it will have no liquid supply to handle. In general principles, therefore, the operation is quite similar to that of the supply and force pump unit of Fig. 1, in that the pump is supplied with liquid at intermittent intervals and runs 35 idly at intermittent intervals.

40 The utility of the priming chamber 160, insofar as such utility relates to a quick supply of oil for the pump when the tank is refilled has already been set forth. Another and more important 45 function of this priming tank, however, is to insure an immediate supply of oil to the pump when the car has been standing idly for some time and regardless of the position of the valve 158. The very restricted seepage passage 164 between the 50 priming chamber and the body of oil in the reservoir is so designed that a very slow seepage of oil is continuously occurring and if the car stands idle for an appreciable length of time the priming chamber will gradually fill up with oil assuring an immediately and possibly a much needed 55 shot of oil at the bearings as soon as the car is set in motion.

What I claim is:

1. A central lubricating system of the character 60 which includes a reservoir, a force pump, a plurality of lubricant filled distributing conduits into which lubricant from the reservoir is forced by the pump, flow-retarding means at the conduit outlets, and timer means synchronized with the pump 65 and acting intermittently to cut off the supply of lubricant thereto from the reservoir.

2. In a continuously operating force pump, means for supplying liquid thereto, a valve in the supply line and means for automatically intermittently closing said valve, whereby said pump 70 will be permitted to exhaust its lubricant supply and periodically will operate idly, said means comprising a valve operating reduction gear train, and means synchronized with the pump for imparting a step by step motion to the reduction gear train. 75

3. In a continuously operating force pump, means for supplying liquid thereto, a valve in the supply line and means for automatically intermittently closing said valve, whereby said pump will be permitted to exhaust its lubricant supply and periodically will operate idly, said means comprising a valve operating reduction gear train, and means synchronized with the pump for imparting a step by step motion to the reduction gear train, one gear of the train serving as a rotary disc inlet valve for the supply line. 80

4. As a new article of manufacture a liquid supply and feed unit for a central lubricating system, said unit including a reservoir, a force pump arranged in the lower portion of the reservoir and means in the reservoir acting automatically to intermittently cut off the flow of liquid from the reservoir to the pump, whereby said pump will be permitted to exhaust its lubricant supply and periodically will operate idly. 90

5. As a new article of manufacture a liquid supply and feed unit for a central lubricating system, said unit including a reservoir, a force pump arranged in the lower portion of the reservoir, means in the reservoir acting automatically to intermittently cut off the flow of liquid from the reservoir to the pump, whereby said pump will be permitted to exhaust its lubricant supply and periodically will operate idly, the supply passage from the reservoir to the pump including a valve, 100 and said passage being vented to a point above the liquid level in the reservoir to maintain atmospheric pressure in said passage at a point between the valve and the pump inlet. 95

6. A supply and force feed unit for central lubricating systems including a reservoir having a filling opening therein, a base casting constituting part of the bottom of the reservoir and defining a pump chamber and pump cylinder, a piston working in the cylinder and operated by an energy source arranged exteriorly of the reservoir, a filter chamber in the base casting through which oil flows in its passage from the reservoir to the pump and having a flow retarding filter pad therein, a valve controlling the flow of oil from the reservoir into the filter chamber and a vent to a point above the liquid level in the reservoir to maintain atmospheric pressure in said passage arranged in the passage between the filter chamber and the pump chamber, whereby said pump 110 will be permitted to exhaust its lubricant supply and will operate idly, when the flow valve is closed. 120

7. A supply and force feed unit for central lubricating systems including a reservoir having a filling opening therein, a base casting constituting part of the bottom of the reservoir and defining a pump chamber and pump cylinder, a piston working in the cylinder and operated by an energy source arranged exteriorly of the reservoir, a filter chamber in the base casting through which oil flows in its passage from the reservoir to the pump, a vented priming chamber communicating with the filter chamber and means for permitting a slow seepage of oil into the priming chamber. 130

8. A supply and force feed unit for central lubricating systems including a reservoir having a filling opening therein, a base casting constituting part of the bottom of the reservoir and defining a pump chamber and pump cylinder, a piston working in the cylinder and operated by an energy source arranged exteriorly of the reservoir, a filter chamber in the base casting through which oil flows in its passage from the reservoir to the pump, a priming chamber, a vent com- 135 140 145 150

- prising a vent pipe, the inlet of which is disposed at the filling opening of the reservoir whereby the priming chamber is filled through the vent pipe as the reservoir is charged.
- 5 9. In a pump, a piston and a movable member for operating the piston, a supply line for the pump, a valve in the supply line, and a reduction gear train synchronized with the pump for periodically opening and closing the valve.
- 10 10. In a pump, a piston and a movable member for operating the piston, a supply line for the pump, a valve in the supply line, a reduction gear train for periodically opening and closing the valve, and means operated from said movable member for actuating the reduction gear train.
- 15 11. In a pump, a piston and a movable member for operating the piston, a supply line for the pump, a valve in the supply line, a reduction gear train for periodically opening and closing the valve, and means operated from said movable member for actuating the reduction gear train, said means including a ratchet and pawl mechanism, the pawl of which is controlled by said movable member and which mechanism imparts a step by step movement to the reduction gear train.
- 20 12. In a lubricating system of the character which includes a central reservoir and a system of distributing piping, a continuously operating pump for forcing lubricant into the distributing system and automatic means for regulating the lubricant feed to the pump and thereby intermittently causing the pump to run idly, said automatic means including means to cause lubricant to be admitted to the pump in charges, each charge being less than the amount of lubricant that the pump will discharge into the system between the periods of admission of said charges.
- 25 13. In a lubricating system of the character which includes a central reservoir and a system of distributing piping, a continuously operating pump for forcing lubricant into the distributing system and automatic means for intermittently causing the pump to run idly, said automatic means comprising a valve controlling the flow of lubricant from the reservoir to the pump and a valve-operating reduction gear synchronized with the movement of the pump.
- 30 14. In a lubricating system of the class which includes liquid filled conduits and a central reservoir, a pump for introducing in rapid succession minute charges of lubricant into the conduit system and means for periodically causing the pump to run idly.
- 35 15. In a lubricating system of the class which includes liquid filled conduits and a central reservoir, a pump for introducing in rapid succession minute charges of lubricant into the conduit system and means for intermittently rendering the pump inoperative to feed lubricant.
- 40 16. In a lubricating system of the type which includes a plurality of branched distributing conduits, a central reservoir and pump unit of the class described comprising a normal flow passage from the reservoir to the pump and a valve controlling said passage, a priming chamber having restricted communication with the reservoir and adapted to be filled by slow seepage, said priming chamber communicating with said flow passage between the valve and the pump.
- 45 17. In a lubricating system of the type which includes a plurality of branched distributing conduits, a central reservoir and pump unit of the class described comprising a normal flow passage from the reservoir to the pump and a valve con-
- trolling said passage, a priming chamber having restricted communication with the reservoir and adapted to be filled by slow seepage, said priming chamber communicating with said flow passage between the valve and the pump, and being freely vented.
- 50 18. In a lubricating system of the type which includes a plurality of branched distributing conduits, a central supply and metering unit comprising a piston, a cylinder, a movable member for operating the piston, a discharge line for the pump, a valve in the discharge line and means moving and rigid with said piston for opening said valve at the termination of the discharging stroke.
- 55 19. A lubricating system of the type which includes a plurality of branched distributing conduits, a central lubricating system of the type which includes a plurality of branched distributing conduits, a central supply and metering unit comprising an inertia weight, a rod adapted to be actuated by said inertia weight and forming a longitudinal bearing therefor and spring disks rigidly positioned on said rod on either side of said weight and adapted to resiliently transfer motion from said weight to said rod, the spacing between said disks being greater than the length of said weight.
- 60 20. In a lubricating system of the type which includes a plurality of branched distributing conduits, a central lubricating system of the type which includes a plurality of branched distributing conduits, a central supply and metering unit comprising an inertia weight, a casing enclosing the same, a connecting rod operatively connected to said weight and passing through the bottom of said casing, a stop chamber in the bottom of said casing and a stop upon said connecting rod adapted to be positioned in said stop chamber, the motion of said rod being restricted by the contact of said stop against the top and bottom of said stop chamber.
- 65 21. In combination with a central lubricating installation having a branched conduit system and a plurality of flow controlling outlets, a supply unit comprising a reservoir and a pump, said pump including a central cylindrical passageway, a piston enclosed in said passageway, a chamber axially aligned with said passageway and positioned therebeyond, an outlet valve in said chamber, an annular chamber encircling said central passageway and an annular valve enclosed in said annular chamber.
- 70 22. In combination with a central lubricating installation including a branched distribution system and a plurality of flow controlling outlets, a central supply unit comprising a pump having a body with a central piston chamber, an axially aligned outlet valve chamber and an annular inlet valve chamber between said piston chamber and said outlet valve chamber, a piston in said piston chamber, a circular valve in said outlet chamber and an annular valve in said inlet chamber.
- 75 23. In a lubricating system for a mechanism having a plurality of spaced bearings to be lubricated, a central lubricant reservoir, a distributing system discharging through a plurality of restricted outlets at the bearings to be lubricated, a pump having a capacity in excess of the current needs of the bearings for force feeding lubricant from the reservoir into the system, means for continuously operating said pump throughout operation of said mechanism actuated automatically by said mechanism and means automati-

cally actuated by said continuously operating means for regulating the flow of lubricant from said reservoir to said pump during operation of said mechanism.

- 5 24. In a lubricating system for a mechanism having a plurality of spaced bearings to be lubricated, a central lubricant reservoir, a distributing system discharging through a plurality of restricted outlets at the bearings to be lubricated, 80
10 a pump having a capacity in excess of the current needs of the bearings for force feeding lubricant from the reservoir into the system, means for continuously operating said pump throughout operation of said mechanism actuated automatically by said mechanism, an intermediate receiver between said reservoir and said pump receiving lubricant from said reservoir and feeding it to said pump, and means continuously driven from the mechanism for intermittently 85
15 supplying lubricant thereto automatically actuated at predetermined intervals in the operation of the mechanism.
- 20 25. In a lubricating system for a mechanism having a plurality of spaced bearings to be lubricated, a central lubricant reservoir, a distributing system discharging through a plurality of restricted outlets at the bearings to be lubricated, a pump having a capacity in excess of the current needs of the bearings for force feeding lubricant from the reservoir into the system, means for 90
25 continuously operating said pump throughout operation of said mechanism actuated automatically by said mechanism, an inlet chamber immediately accessible to said pump, said chamber being provided with an air vent extending above the lubricant level of the reservoir so that said 95
30 inlet chamber will always be open to the atmosphere and atmospheric pressure will be maintained therein, and a plurality of flow passageways from said reservoir to said pump, one of which is provided with a restriction and another 100
35 of which is provided with an intermittent actuated valve.
- 35 26. In a lubricant system for a mechanism having a plurality of spaced bearings to be lubricated, a central lubricant reservoir, a distributing system discharging through a plurality of restricted outlets at the bearings to be lubricated, a pump having a capacity in excess of the current 105
40 needs of the bearings for force feeding lubricant from the reservoir into the system, means for continuously operating said pump throughout operation of said mechanism actuated automatically by said mechanism, a lubricant flow retarding means positioned between said pump and said 110
45 reservoir and means ahead of said flow retarding means to prevent flow of lubricant periodically from said reservoir to said pump during operation of said mechanism.
- 45 27. In a lubricating system for a mechanism having a plurality of spaced bearings to be lubricated, a central lubricant reservoir, a distributing system discharging through a plurality of restricted outlets at the bearings to be lubricated, a pump having a capacity in excess of the current 115
50 needs of the bearings for force feeding lubricant from the reservoir into the system, means for continuously operating said pump throughout operation of said mechanism actuated automatically by said mechanism, and means for varying the discharge of said pump into said system by regulating its supply during operation of said mechanism automatically driven by said mechanism.
- 55 28. In a lubricating system for a mechanism having a plurality of spaced bearings to be lubricated, a central lubricant reservoir, a distributing system discharging through a plurality of restricted outlets at the bearings to be lubricated, a pump having a capacity in excess of the current 120
60 needs of the bearings for force feeding lubricant from the reservoir into the system, means for continuously operating said pump throughout operation of said mechanism actuated automatically by said mechanism, means for maintaining a supply of lubricant immediately accessible to 125
65 said pump, and means continuously driven from the mechanism for feeding said supply at intervals with quantities of lubricant from said reservoir which will not suffice to permit the pump to feed at full capacity during such intervals.
- 70 29. In a lubricating system for a mechanism having a plurality of spaced bearings to be lubricated, a central lubricant reservoir, a distributing system discharging through a plurality of re- 130
75

stricted outlets at the bearings to be lubricated, a pump having a capacity in excess of the current needs of the bearings for force feeding lubricant from the reservoir into the system, means for continuously operating said pump throughout operation of said mechanism actuated automatically by said mechanism, means for maintaining a supply of lubricant accessible to the pump, and constant and intermittent feed means to permit lubricant to flow from said reservoir to said supply.

29. In a lubricating system for a mechanism having a plurality of spaced bearings to be lubricated, a central lubricant reservoir, a distributing system discharging through a plurality of restricted outlets at the bearings to be lubricated, a pump having a capacity in excess of the current needs of the bearings for force feeding lubricant from the reservoir into the system, means for continuously operating said pump throughout operation of said mechanism actuated automatically by said mechanism, an inlet chamber immediately accessible to said pump, said chamber being provided with an air vent extending above the lubricant level of the reservoir so that said inlet chamber will always be open to the atmosphere and atmospheric pressure will be maintained therein, and a plurality of flow passageways from said reservoir to said pump, one of which is provided with a restriction and another 105
35 of which is provided with an intermittent actuated valve.

30. In a central lubricating installation for a mechanism having a plurality of spaced bearings, including a branched piping system leading 110
115 to said bearings and having metering outlets to said bearings, a continuously operating pump actuated automatically only upon operation of said bearings and discharging its entire output into said system, said pump comprising means for supplying liquid thereto, and means for intermittently cutting off the liquid supply, whereby said pump will be permitted to exhaust its lubricant supply and will operate idly.

31. In a central lubricating installation for a 120
mechanism having a plurality of spaced bearings, including a branched piping system leading to said bearings and having metering outlets to said bearings, a continuously operating force pump actuated automatically only upon operation of 125
130 said bearings and discharging its entire output into said system, said pump comprising means for supplying liquid thereto, a valve in the supply line and means for automatically intermittently closing said valve, whereby said pump will be permitted to exhaust its lubricant supply and will operate idly.

32. In a central lubricating installation for a mechanism having a plurality of spaced bearings, including a branched piping system leading to 135
140 said bearings and having metering outlets to said bearings, a force pump actuated automatically only upon operation of said bearings and discharging its entire output into said system, said pump comprising means for supplying lubricant thereto, a valve in the supply line and means for automatically intermittently closing said valve, whereby said pump will be permitted to exhaust its lubricant supply and will operate idly, said means comprising a valve operating reduction gear train.

JOSEPH BIJUR.
